UNITED STATES PATENT OFFICE.

MILTON A. MCKEE, OF NEW YORK, N. Y., ASSIGNOR TO C. B. COTTRELL & SONS COMPANY, OF NEW YORK, N. Y., A CORPORATION OF NEW JERSEY.

PROCESS OF TREATING PRINTING-PLATES.

No. 872,630.

Specification of Letters Patent.

Patented Dec. 3, 1907.

Application filed August 30, 1904, Serial No. 222,713. Renewed May 20, 1907, Serial No. 374,726.

To all whom it may concern:

Be it known that I, MILTON A. MCKEE, a citizen of the United States, and resident of the borough of Manhattan, in the city and 5 State of New York, have invented a new and useful Improvement in the Process of Treating Printing-Plates, of which the following is a specification.

This present invention consists in the 10 process of treating the faces of electrotype or stereotype printing plates for the purpose of correcting or preventing a hard printing impression on the edges of the plates.

In the use of printing plates it has been 15 found that as the impression cylinder rolls up on to the printing surface of a plate, the edge of the plate is impressed into the surface of the cylinder for the reason that the plate support and bed are unyielding while 20 the surface of the impression cylinder is more or less yielding because it is packed with a series of sheets of paper. The opposite edge of the plate also produces an indentation in the cylinder as the cylinder 25 leaves the plate. This serves to produce a hard imprint along the edges of the plate and also indents the sheet being printed sufficiently to emboss it at those points. The method now in practice for obviating 30 this difficulty is to tear out the make ready sheets which constitute the packing on the impression cylinder. This method is not satisfactory for the reason that the impression surface of the cylinder should not be 35 lowered for the edges of the plates but should remain at a uniform level. To produce the best results the edges of the plate should be lowered.

My invention consists in the process here- 40 after described of treating the plates so as to depress their printing faces along the edges thereof.

The procedure is as follows: An impression of the plates which are to constitute the 45 printing form is pulled. Several strips of French folio paper are then cut. A strip of this paper is pasted on each side edge of the proof so as to overlap the impression of the reading matter a short distance as, for in- 50 stance about one sixteenth of an inch. Another strip of paper is then pasted on the top of the previously pasted strip so as to lap over the reading matter a short distance beyond the first named strip as, for instance, 55 from one sixteenth to one eighth of an inch.

This process may be repeated until the face of the proof is raised continuously along its edges to produce a matrix of the required form, with each of its raised portions of the same height throughout its length. The 60 matrix is then laid upon the bed of a shaving machine. The printing plate is then placed face down upon the matrix and registered therewith. The back of the plate is then shaved until it is perfectly flat, this 65 shaving process serving to remove the metal from the back of the plate and where it has been raised by the engagement of the side edges of the face of the plate with the raised portions of the matrix. The matrix and 70 plate are then removed from the bed of the shaving machine. The matrix is placed upon a sheet of polished brass, preferably about an eighth of an inch thick, the face of the matrix being up. The plate is then 75 registered face downward on the matrix and the sheet of brass, matrix and plate are slid in between the two parallel surfaces of a heating box. The follower of the heating box is screwed downward until it just 80 touches the back of the plate and is allowed to rest there until the brass and printing plate are both thoroughly heated. Pressure is then applied and the plate being in a semi-soft state, takes on the character of the 85 matrix. The pressure is then removed and the brass, matrix and plate are removed from the heating box and inserted between the parallel surfaces of a cooling box. Pressure is there applied while the plate is 90 being allowed to cool. The plate is then ready to be put upon the press.

It will be found that when the form is made up and put upon the bed of the press and the impression surface of the cylinder 95 packed to one uniform thickness, that the first impression upon a sheet will be correct and will not show a heavy impression or embossing along the edges of the printed matter thereon, thus producing an even impres- 100 sion throughout. Furthermore, the life of the plate is increased at least fifty per cent.

The invention is illustrated in the accom- 105 panying drawings in which

Figure 1 represents a plan view of the completed matrix, portions of the side strips which form the raised parts of the matrix being broken away to more clearly show the method of lapping the strips over the edges of the printed matter on the proof; Fig. 2 is 110

a transverse section taken in the plane of the line A—A of Fig. 1; Fig. 3 is a transverse section showing the plate and matrix in a shaving machine, the back of the plate being subjected to the shaving operation; Fig. 4 is a transverse section through the plate showing the form which it would assume when removed from the shaving machine; Fig. 5 is a sectional view of the plate and matrix shown 10 in connection with the flat bed and follower of a heating box or press, Fig. 6 is a similar view showing the plate and matrix under pressure in a cooling box, and Fig. 7 is a section of the finished plate.

15 The proof sheet is denoted by 1. The continuous raised portion at each side of the proof sheet for completing the matrix is of the same height throughout its length and is herein shown as composed of three strips of 20 paper, 2, 3 and 4, the strip 2 being pasted directly on to the proof 1 with its inner edge overlapping the printed matter thereon to the desired point. The strip 3 is shown as projecting a short distance further on to the 25 printed matter of the proof 1 and the strip 4 as projecting still further on to the printed matter.

The plate is denoted by 5. It is registered 30 with the matrix with the side edges of its printing face in engagement with the raised portions of the matrix. The plate and matrix are placed in a shaving machine between the bed 6 and the knife 7 and run through the said machine. The plowing and pressing 35 action of the knife serves to remove the superfluous metal on the back of the plate at its edges, the shavings being herein designated by 8, until the back of the plate is level. The plate and matrix are then removed from 40 the shaving machine. The matrix is placed face up upon a sheet of brass 9. The plate is registered therewith face downward and the brass sheet, matrix and plate are inserted between two smooth flat parallel surfaces 45 faces 10, 11, such, for instance, as the bed and follower of a heating box or press, which are heated to a suitable degree of temperature to soften the metal of the plate so as to cause it to assume the desired form. The 50 brass sheet, matrix and plate are, after being subjected to pressure on the heating box, removed therefrom and placed between two flat parallel surfaces 12, 13, of a cooling box where they are also subjected to pressure.

55 This will cause the plate to retain its form with the edges of its printing face depressed evenly and the plate will then be ready to be put upon the press ready to print.

It is to be understood that this method of 60 treating printing plates may be successfully used in connection with the process set forth in my United States Letters Patent No. 760,235 dated May 17, 1904, for treating uneven printing plates for evening their surfaces. When used in connection with the

process referred to, the two matrices would both be placed upon the bed of a shaving machine in connection with the plate and the plate shaved in the usual manner. The plate would then be subjected to the heating and 70 cooling operations without the use of the matrices used for evening the faces of the plate.

What I claim as my invention is:

1. The process of treating printing plates 75 for the purpose of correcting or preventing a hard printing impression on the edges of the plates, which consists in subjecting the plate to pressure while its face is in contact with a matrix having a continuous raised portion of 80 the same height throughout its length along each of the side edges of the plate.

2. The process of treating printing plates 85 for the purpose of correcting or preventing a hard printing impression on the edges of the plates, which consists in subjecting the plate to pressure while its face is in contact with a matrix having a continuous raised portion of 90 the same height throughout its length along each of the side edges of the plate and subjecting the plate to pressure and heat between two parallel surfaces while the plate is in contact with the matrix.

3. The process of treating printing plates 95 for the purpose of correcting or preventing a hard printing impression on the edges of the plates, which consists in subjecting the plate to pressure while its face is in contact with a matrix having a continuous raised portion of 100 the same height throughout its length along each of the side edges of the plate, subjecting the plate to pressure and heat between two parallel surfaces while the plate is in contact with the matrix and finally cooling the plate while under pressure.

4. The process of treating printing plates 105 for the purpose of correcting or preventing a hard printing impression on the edges of the plates, which consists in subjecting the plate to a shaving operation while its face is in contact with a matrix having a continuous raised portion of 110 the same height throughout its length along each of the side edges of the plate.

5. The process of treating printing plates 115 for the purpose of correcting or preventing a hard printing impression on the edges of the plates, which consists in subjecting the plate to a shaving operation while its face is in contact with a matrix having a continuous raised 120 portion of the same height throughout its length along each of the side edges of the plate and subjecting the plate to pressure and heat between two parallel surfaces while in contact with the matrix.

6. The process of treating printing plates 125 for the purpose of correcting or preventing a hard printing impression on the edges of the plates, which consists in subjecting the plate to a shaving operation while its face is in con-

tact with a matrix having a continuous raised portion of the same height throughout its length along each of the side edges of the plate, subjecting the plate to pressure and heat between two parallel surfaces while in contact with the matrix and finally cooling the plate while under pressure.

7. The process of treating printing plates for the purpose of correcting or preventing a hard printing impression on the edges of the plates, which consists in placing the plate with its face in contact with a matrix having a continuous raised portion of the same height throughout its length along each of the side edges of the plate, then while in such contact, subjecting the plate at the same time to pressure against the matrix by the act of a shaving operation on its back, afterward subjecting the plate and matrix to pressure and heat between two parallel surfaces and finally subjecting the plate to a cooling operation while under pressure.

10 15 20 25 30 35

for the purpose of correcting or preventing a hard printing impression on the edges of the plates, which consists in placing the plate with its face in contact with a matrix having a continuous raised portion of the same height throughout its length along each of the side edges of the plate, then while in such contact, subjecting the plate at the same time to pressure against the matrix by the act of a shaving operation on its back, afterward subjecting the plate and matrix to pressure and heat between two parallel surfaces and finally subjecting the plate to a cooling operation while under pressure.

In testimony, that I claim the foregoing as my invention, I have signed my name in presence of two witnesses, this ninth day of August 1904.
